UNITED STATES PATENT OFFICE.

HENRY KIELBERG, OF MARTINS FERRY, OHIO.

COILING KEY FOR COLLAPSIBLE TUBES.

Application filed October 3, 1927. Serial No. 223,601.

This invention relates to a device for coiling collapsible tubes to effect removal of the contents of such tubes, and it has for its primary object to provide a simple and inexpensive device or instrument adapted for application to an end of a collapsible tube of the character commonly employed as containers for pastes, paints and the like, whereby such tube may conveniently be rolled for ejecting 10 the contents through the open end of the latter.

A further object is to provide an instrument of the character mentioned by means of which is obviated the necessity for the application 15 to the collapsible tube body of finger pressure, which latter tends unduly to distort the tube and which, ordinarily, is ineffectual for completely removing the contents of the latter.

In describing the invention in detail, reference is herein had to the accompanying drawings, in which—

Figure 1 is a front elevation of the invention;

Figure 2 is a side elevation of the same;

25 Figure 3 is an end elevation;

Figure 4 is a front elevation of a slightly modified form of the invention.

The invention consists of a key-like one-piece structure which includes a body 1, preferably of cylindrical form in cross section, and a transversely disposed finger piece 2 located at one end of said body. As shown in Figs. 1 to 4, inclusive, the device is constructed of sheet metal, the body 1 thereof being bent into approximately tubular form with the opposite, or approaching, edges spaced apart to form a longitudinally extending slot 3. Said slot is designed to receive therein the closed bottom end of a collapsible metal tube 4, shown in broken lines in Figs. 1, 2 and 3, following which said tubular body is rotated to coil thereon the metal of such tube, thereby to exert pressure for expelling the tube contents from its open end, as desired.

45 The side of the tubular body 1 opposite the slot 3 is extended at one end to form the finger piece 2 which consists of two oppositely disposed wings 2^a, each of which is made of concavo-convex form designed conformably 50 to fit the ball of a thumb or finger, thereby to facilitate the grasping of the finger piece by the user. As shown, the wings 2^a are reversely disposed.

It is preferred that one of the approaching, or slot-defining edges of the tubular body 1 shall present one or more tooth-like projections 5 located in the circumferential plane of said body, and that the confronting edge shall be correspondingly recessed, as shown at 6, thereby to render the slot 3 slightly sinuous throughout a portion of its length. Said projections or teeth 5 are designed, upon rotation of the instrument relative to the collapsible tube, to seat in depressions thereby formed in the metal of the tube for securing 65 the instrument against chance displacement from its operative position. As is apparent, since the metal of the tube is readily flexible, introduction of the flattened closed end of said tube in the sinuous slot 3 may be readily 70 effected.

The structure shown in Fig. 4 differs from that disclosed in Fig. 1 only in that a plurality of teeth 5 are substituted for the single tooth of the last mentioned figure.

75 As is obvious, the instrument is permanently carried by the tube following application to the latter, and, in the continued use thereof, the entire body portion of the tube is coiled upon the body, thus effecting removal 80 of substantially the entire contents.

What is claimed is—

1. A key-like device of the character described comprising a tubular sheet metal body having at one end thereof a finger-piece 85 whereby said body may be rotated, the confronting edges of said body being correspondingly serrated and spaced apart to form a sinuous longitudinally extending slot adapted for the reception of the flattened end of a 90 collapsible tube.

2. A key-like device of the character described comprising a tubular sheet metal body having at one end thereof a finger-piece whereby said body may be rotated, one of the 95 confronting edges of said body carrying intermediate its ends a tooth-like projection and the opposite edge being provided with a correspondingly located recess, said edges being spaced apart to form a slot adapted for 100 the reception of the flattened end of a collapsible tube.

In testimony whereof, I affix my signature.

HENRY KIELBERG,
